UNITED STATES PATENT OFFICE.

JOSEPH ZWILLING, OF NEW YORK, N. Y., ASSIGNOR TO WESTERN ELECTRIC COMPANY,
OF NEW YORK, N. Y., A CORPORATION OF ILLINOIS.

PROTECTOR.

1,106,911.

Specification of Letters Patent. Patented Aug. 11, 1914.

Application filed May 8, 1914. Serial No. 837,201.

To all whom it may concern:

Be it known that I, JOSEPH ZWILLING, a citizen of the United States, residing at New York, in the county of New York and State 5 of New York, have invented certain new and useful Improvements in Protectors, of which the following is a full, clear, concise, and exact description.

This invention relates to protective apparatus for electrical currents, and more particularly to a combined apparatus adapted 10 to protect a circuit against instantaneous high pressure discharges, such as lightning.

The object of this invention is to provide 15 an improved method of mounting such apparatus in a convenient manner with all of the parts well insulated and protected against moisture.

In accordance with this invention the apparatus 20 is mounted between circuit-connecting springs or plates secured to a common base.

One feature of the invention relates to the 25 means for supporting the circuit-connecting springs or plates in the base in such a manner that they may be protected by a moisture-proof covering beneath the base.

Another feature of the invention is the 30 form of spring or plate provided for preventing the moistureproof covering from flowing through to the top of the base and covering the contacting portions of the springs or plates.

The invention is illustrated in the accompanying drawings in which—

Figure 1 is a plan of a protector embodying the invention; Fig. 2 is a sectional view taken on the line 2—2; Fig. 3 is a perspective view of the circuit-connecting springs or 40 members; Fig. 4 is an enlarged sectional view taken on the line 4—4; Fig. 5 is a perspective view of the ground-connecting member or plate.

The protector is comprised of a base 1, 45 having formed integral therewith an annular boss 3, which has threads formed upon its inner surface adapted to register with those upon a screw-cap 25. Recesses are made in the bottom surface of the base 1 for the purpose of countersinking the circuit-connecting spring members or plates.

The circuit-connecting spring members comprise a plurality of resilient members 5, 5, each having a vertical body-portion 6, 55 a horizontal body-portion 7, and a bent-over

portion 8 as is illustrated in detail by Fig. 3. The bent-over portion 8 is of greater width than the horizontal portion 7, which permits the edge thereof to be formed into a cup or flange 9. The cup or flange 9 is of sufficient depth so as to conceal and thereby protect the horizontal portion 7 when the resilient member 5 is mounted in the base 1. The vertical portion 6 is curved in a manner substantially as shown, for the purpose 60 of causing said portion to engage or grip the carbon blocks 19, 19. A hole 10 is bored through the portions 7 and 8, which permits the insertion of the bolt of a binding post 18 when resilient member 5 is mounted in the 70 base 1.

A ground member or plate 11 carries an extension member 12, which lies in a plane at right angles to that of said ground plate 11. Lugs 14, 14, formed upon the vertical 75 edges of the ground plate 11, function as a guide for the carbon blocks 19, 19, and a lug 15, formed at the center near the base of said ground plate 11, functions as a stop or support to limit the downward movement 80 of said carbon blocks 19, 19. The ground plate 11 is positioned intermediate the ends of extension member 12, so that said member 12 is divided into unequal lengths 16, 17. The short length 16 functions to cover aperture 21 when the plate 11 is mounted in base 1 by means of the bolt of binding post 18 passing through hole 13 made in the long length 17.

The resilient members 6, 6 and the ground 90 plate 11 are admitted into the protector chamber through apertures 20, 20 and 21 made in the base 1. When the protector is assembled, the ground plate 11 is positioned intermediate the resilient members 5, 5, 95 which are mounted opposing each other. The tension of resilient members 5, 5 is toward the ground plate 11, which provides a means for holding the carbon blocks 19, 19 against said ground plate 11, and the lugs 100 14, 14 and 15 prevent the dislocation of said carbon blocks 19, 19 when placed in position. The flange 9 on the resilient members 5, 5 and the short length 16 of extension member 12 of the ground plate 11, completely 105 cover the apertures 20, 20 and 21, respectively, so that when the recesses formed in the base 1 are filled with some moistureproof substance, for the purpose of excluding the moisture from the protector chamber, none 110

of said substance can flow into said chamber.

What is claimed is:

1. In a protective apparatus, a plurality of springs or contact plates, a base upon which said springs or contacts are mounted with a portion thereof upon each side of said base, a moistureproof insulating compound applied to the portion of said springs or plates upon one side of said base, and means for preventing said compound spreading over the portion of said springs or plates upon the opposite sides of said base.

2. In a protective apparatus, a base having openings therethrough and recessed in one face thereof, contact springs or plates extending through said openings, and means on said contact springs or plates fitting snugly into said recesses and covering said openings.

3. In a protective apparatus, a supporting base provided with openings therethrough and recesses upon one face, and supporting springs or plates for said protective apparatus extending through said openings, said supporting springs or plates being provided with a bent-over portion adapted to fit into said recesses and cover said openings.

4. In a protective apparatus, a supporting

base provided with openings therethrough 30 and recesses upon one face, and supporting springs or plates for said protective apparatus extending through said openings, said supporting springs or plates being provided with a bent-over portion, said bent-over portion 35 having its edge formed into a lip or flange which is adapted to fit into said recesses and cover said openings.

5. In a protective apparatus, a supporting base provided with openings therethrough 40 and recesses upon one face, and supporting springs or plates for said protective apparatus extending through said openings, said supporting springs or plates being provided with a bent-over portion, said bent-over portion 45 having a greater width than the body-portion of said supporting springs or plates, and having the part adjacent to the edge of said bent-over portion formed into a lip or flange adapted to fit into said recesses and 50 cover said openings.

In witness whereof, I hereunto subscribe my name this 6th day of May, A. D. 1914.

JOSEPH ZWILLING.
